BLOUSE

Nels C. Moss, St. Louis, Mo.

Application September 22, 1958, Serial No. 52,707

Term of patent 14 years

(Cl. D3—25)

The characteristic feature of my design for a blouse resides in the configuration of vents, provided at the neck and under each arm, said vents being crossed by strips.

I claim:

The ornamental design for a blouse, as shown and described.
